UNITED STATES PATENT OFFICE.

CHARLES G. CARLSON, OF CHICAGO, ILLINOIS.

CURTAIN STRETCHER.

Application filed February 6, 1926. Serial No. 86,403.

The present invention relates primarily to the curtain stretcher as a whole, that is to say, to the frame work comprising the four pin rails disposed in rectangular relation to one another, together with the corner clamps which serve to hold the pin rails rigidly together when the component parts of the frame are assembled.

In certain prior constructions, with which I am familiar, it is the practice to unite all four corners of the frame by means of clamping members of uniform character, but I have found that better results may be obtained by the use of clamping members of diverse character, one pair of clamps being provided to unite two of the corners with the rails in abutting relation to one another, and another pair of clamps, of a different type, being employed to unite the remaining two corners with the pin rails in overlapping relation. This method of building up or assembling the constituent portions of the frame results in precision and accuracy of adjustment, and also provides a frame possessing great rigidity and resistance to distortion from its true rectangular configuration.

The present invention is directed to the frame as a whole, and also to the special form of clamp which is utilized for uniting the overlapped corners, which clamp is of a character which tends to square up the frame as a whole when the clamps are adjusted to place, and also provides a corner brace of peculiar character for reinforcing and stabilizing the frame. The companion pair of clamps, which are used to unite the corners afforded by the butt ended pin rails, is also believed to possess features of novelty, but this special form of clamp per se forms the subject of a separate application and will be here claimed only in its combined relation to the frame as a whole.

Further objects and details will appear from a description of the invention where-

in—

Figure 1 shows a plan view of the frame as a whole, sections of the rails being broken out to reduce the size of the figure to appropriate dimensions;

Fig. 2 is a longitudinal sectional view of the special form of bracing clamp for the overlapped corners showing the position of the pin rails in dotted lines;

Fig. 3 is a section of the same taken at right angles to the disclosure of Fig. 2;

Fig. 4 is an end elevation of said clamp;

Fig. 5 is a view showing both forms of clamp in position at opposite ends at one of the pin rails.

The frame comprises four pin rails including what may, for convenience, be termed side rails 10 and 11, and end rails 12 and 13. Preferably, though not necessarily, the so-called side rails are somewhat longer than the end rails, but obviously the dimensions of the respective rails will conform to the use for which the stretcher is intended.

The end rails 12 and 13 lie in spaced parallel relation, and on one side of the frame their ends are overlapped or crossed by the side rail 10 extending in right angle relation to the end rails. The overlapped ends are embraced by a diagonally disposed bracing clamp 14 of U-shaped formation comprising parallel spaced side plates 15 and a connecting cross head 16 through which extends an adjusting screw 17 provided with a handle 18.

The brace clamp as a whole is formed of a strip of sheet metal bent to the proper shape, and the center of the head has a metal struck inwardly to afford a boss 19 through which the adjusting screw is threaded. In order to more perfectly reinforce the head and stiffen it to withstand the thrust of the screw, the side edges of the cross head are turned inwardly to afford flanges 20 which give a channel-like formation to the head as a whole.

The inner end of the screw 17 is pointed and bears against the inner angle of a corner abutment 21 of right angular formation comprising bearing faces 22 and 23 bent at right angle relation to one another and also comprising triangular end walls 24 which give to the corner abutment, as a whole, the configuration of a hollow half cube cut through diagonally opposed edges. It is preferred to form the corner abutment from a single plate of material with the ends bent inwardly from one of the side faces.

The corner abutment 21 is fitted to slide between the side plates 15 of the present clamp, which plates, near the head ends, are provided with longitudinally extending

slots 25 which furnish a pair of guideways for the reception of tongues 26 which are struck outwardly from the end walls of the corner abutment 21, the arrangement being such that when the adjusting screw is turned inwardly, it will exert a thrust against the inner angle of the abutment and force the same inwardly against the proximate faces of the overlapped pin rails. As indicated in Fig. 3, the spread of the side plates 15 is sufficient to embrace the pin rails when overlapped, and the length of the abutment 21 is sufficient to afford full bearing surface against the subtended portions of the pin rails.

The adjustable abutment 21 co-operates with a fixed corner abutment 27 embraced between the opposite ends of the side plates 15 and held in fixed relation thereto by the provision of a pair of screws 28 which act in conjunction with tongues 29 struck outwardly from the free edges of the end walls 30 of the abutment in position to lie within companion recesses 31-31 in the end edges of the plates 15, the arrangement being such that pivotal movement upon the screws 28 is thus prevented. The general configuration of the end abutment 27 is precisely similar to that of the abutment 21, the end abutment having angularly disposed walls 32 which bear against the proximate faces of the pin rails, in opposed relation to the contact afforded by the adjustable abutment 21, as clearly indicated in Fig. 2, from which it will appear that the co-acting abutments fit squarely within the opposing outer angles at the overlapped corner of the frame.

The remaining two corners afforded by the butted pin rails, which lie in flush relation to one another, are held in assembled relation by the provision of a pair of loop shaped clamps 33 each comprising side plates 34 and 35 and a cross head 36. The cross head has entered therethrough an adjusting screw 37 which bears against the interior of a U-shaped abutment 38, the side walls 39 of which are guided within recesses 40 in the side edges of the cross head 36, the arrangement being such that a turning up of the screw 37 will cause advancement of the abutment 38 which will thus exert pressure against the edge of the pin rail 11. The side plates 34 and 35 are connected to the end of the end rail 13 by means of rivets 41 and 42, or in any other suitable manner.

The special details of the clamp 35 are not deemed to constitute a part of the present invention, and in so far as the general combination is concerned, other types of clamps, adapted to hold the parts in flush abutting relation, might be substituted, so that it is not deemed necessary to describe or illustrate such details with greater precision than is here indicated. The pin rails 65 are themselves of the type common in cur-

tain stretcher construction, being recessed behind their inner edges, as at 43, and provided with the usual undercut channels 44 within which the pins 45 are slidably mounted.

It will be observed that in the construction shown, the loop shaped clamps 33 are permanently united to and extend outwardly from the ends of the end rails 12 and 13 while the corner brace clamps 14 are not permanently united to the rails, but constitute separable fixtures adapted to be slipped in place in diagonal relation to the overlapped corners when the frame is being assembled.

In order to assemble the present frame, the clamps 33 are first loosened up sufficiently to permit insertion of the side rail 11 through the spaces thus afforded, after which the end rails 12 and 13 are adjusted to afford the proper space relation which will be indicated by the usual graduated scale common in devices of this character. After the parts have been thus adjusted, the screws 37 will be tightened up, forcing the U-shaped abutments 38 against the proximate edge portions of the rail 11 until the parts are held in sufficiently firm contact to prevent slipping.

With three sides of the frame thus assembled, the rail 10 will be slipped through the corner brace clamps, which are loosened up sufficiently to permit of this adjustment, after which the thumb screws 17 will be turned down to force the adjustable abutments firmly into contact with the proximate corners. This adjustment will have the effect of exactly squaring up the frame as a whole for the reason that the co-acting corner abutments each present their contact faces in right angle relation to one another, so that when the two abutments are forced inwardly with respect to one another, they will adjust and maintain the pin rails in exact right angle relation.

By tightening up the clamps 34, no slipping or sliding of the butt ended rails will be permitted during the final adjustment of the corner clamps, so that the tightening of the latter will square up the frame, and, at the same time, the overlapped relation of these corners, and the diagonal positioning of the clamps will effect a firm bracing or reinforcement of the frame as a whole and afford a much more rigid union of the parts than if the rails were also butt ended on this side.

From the foregoing, it will be apparent that the frame as a whole comprises rails which are butt connected upon one side and overlapped and diagonally braced on the other side, and that the conjunction and co-operation of these two methods of securement results in a union of the component parts of the frame which possesses special advantages both by reason of the inherent

rigidity of the union afforded by the brace clamps, and by reason of the squaring up effect which such clamps afford during the assembling of the frame.

5 I claim:

1. In a device of the class described, the combination of four rails arranged in the form of an open frame, the rails at two of the corners being assembled in flush relation to one another and the rails at the other two corners being arranged in overlapped relation to one another, means for engaging the flush corners, diagonally disposed brace clamps embracing the overlapped corners 15 provided with oppositely facing abutting members adapted to engage diagonally opposed angles at such corners, and means for adjusting said opposed abutments relatively to one another to engage and hold said corners, each of said opposed abutments being provided with contact faces in oppositely converging relation to one another and lying in right angle relation to one another to square up said corners, substantially as de- 20 scribed.

2. In a device of the class described, the combination of four rails arranged in the form of an open frame, the rails at two of the corners being assembled in flush relation to one another and the rails at the other two corners being arranged in overlapped relation to one another, means for engaging the flush corners, diagonally disposed brace clamps embracing the overlapped corners 25 provided with abutting members adapted to engage diagonally opposed angles at such corners, means for adjusting said opposed abutments relatively to one another to engage and hold said corners, each of said opposed abutments comprising right angularly disposed contact faces adapted to square the frame and connecting end walls, and an adjusting screw carried by a fixed portion of each clamp and bearing against the proximate abutment, substantially as described.

3. In a device of the class described, a brace clamp comprising in combination spaced side plates and a connecting cross head at one end thereof, an adjusting screw 30 entered through the cross head, and a pair

of abutments having inwardly oppositely facing angularly disposed contact faces in oppositely converging relation to one another, one of the abutments being fixedly secured between the side plates, and the other 55 abutment being slidable between said plates and being engaged by said adjusting screw, substantially as described.

4. In a device of the class described, a corner brace clamp comprising in combination a pair of side plates connected at one end by a cross head and each provided at a point adjacent thereto with an elongated slot, the edges of the cross head being turned inwardly to afford reinforcing flanges, an adjustable abutment embraced between the side plates of the clamp near the head end thereof and being formed to provide inwardly facing contact faces at right angles to one another and being provided with end walls 70 in close contact with the inner walls of the side plates, said end walls having outwardly projecting tongues slidably engaging said slots, an adjusting screw entered through the head and bearing against said adjustable 75 abutment, and a similarly formed oppositely disposed abutment at the far end of the clamp rigidly secured between the side plates thereof, substantially as described.

5. In a device of the class described, a corner brace clamp comprising in combination a pair of side plates connected at one end by a cross head and each provided at a point adjacent thereto with an elongated slot, an adjustable abutment embraced between the side 80 plates of the clamp near the head end thereof and being formed to provide inwardly facing contact faces at right angles to one another and being provided with end walls 85 in close contact with the inner walls of the side plates, said end walls having outwardly projecting tongues slidably engaging said slots, an adjusting screw entered through the head and bearing against said adjustable 90 abutment, and a similarly formed oppositely disposed abutment at the far end of the clamp rigidly secured between the side plates 95 thereof, substantially as described.

CHARLES G. CARLSON.
